UNITED STATES PATENT OFFICE.

LOUIS I. SHRADER, OF NEW ALBANY, INDIANA.

APPARATUS FOR FUMIGATING TELEPHONE INSTRUMENTS.

No. 872,204.

Specification of Letters Patent.

Patented Nov. 26, 1907.

Application filed May 29, 1907. Serial No. 376,357.

To all whom it may concern:

Be it known that I, LOUIS I. SHRADER, a citizen of the United States, residing at New Albany, in the county of Floyd and State 5 of Indiana, have invented a new and useful Apparatus for Fumigating Telephone Instruments, of which the following is a specification.

This invention has reference to improvements in apparatus for fumigating telephone instruments, and its object is to provide an inexpensive and effective means for the application of disinfecting agents to the mouthpiece of a transmitter and the ear-piece of a receiver without the necessity of disturbing the working relations of these parts.

The invention consists essentially of a receptacle arranged for the ready insertion of the parts of the telephone instruments 20 subject to contamination, with means for applying the disinfecting agent and confining the fumes or vapors given off therefrom so that the telephone instruments shall be effectually subjected to the action of the 25 disinfectant and thus cleansed.

Specifically, the invention comprises a box or case having at one end a means for the introduction of the disinfectant, preferably in a form which may be lighted and so give 30 off fumes fatal to germ life, while near the other end of the case is provided an opening adapted to receive the mouthpiece of a transmitter after the same has been removed from the body of the instrument and by means of 35 which the case may be fastened to the transmitter head. Adjacent to the opening receiving the mouthpiece of the transmitter is another opening for receiving the ear-end of a telephone receiver, while a closure is 40 provided which will confine the receiver in place so that both instruments may be subjected to the action of the disinfectant or germicide at the same time and for as long a time as may be desired.

The invention will be fully understood from the following detailed description taken in connection with the accompanying drawings forming part of this specification, in which,

Figure 1 is a section through the disinfecting receptacle, showing the telephone instruments in place; and Fig. 2 is a perspective view of the instrument unattached to the telephone.

Referring to the drawings, there is shown an ordinary telephonic receiver 1 and an

ordinary telephonic transmitter head 2 mounted upon an arm 3 and provided with a removable mouthpiece 4, common to such instruments. The telephonic instruments 60 are of the usual construction and need no further or detailed description.

The disinfecting apparatus comprises a rectangular box 5 having one end 6 of reduced area and having in one of its side walls 65 a through opening 7. The reduced end 6 of the box 5 is shown as having its walls inwardly curved, but the walls may be straight so that this end is frusto-pyramidal.

In the side wall of the casing 5 on the opposite side from the opening 7 and about half way of the height of the casing, considering the portion 6 as the bottom, is a cylindrical through opening 8 which may be provided, if desired, with a bead or reinforcement 9, 70 and above this opening 8 is another opening 10 having a rounded bottom or base and extending to the upper edge of the side wall of the casing. The other end of the casing is open and applied thereto is a removable 80 cover 11 arranged to fit snugly over this end and close the same against any material escape of fumes or vapors. Fast to the cover 11 or, if desired, separate therefrom, is a plate 12 extending down back of the upper 85 extension of the opening 10 and having its bottom formed with a semi-circular recess 13 coacting with the lower rounded portion of the opening 10 to constitute a circular passageway into the interior of the casing 5. 90 The lower or curved portion of the opening 10 may be provided with a semi-circular reinforcement 14, as indicated.

Now, by removing the cover 11 access may be had to the interior of the casing 5. By 95 unscrewing the mouthpiece 4 from the transmitter head 2 this mouthpiece may be inserted into the casing and then through the opening 8, and, if desired, again screwed into the head 2, so that the entire casing 5 will be 100 supported by the telephone transmitter head with the mouthpiece 4 interior to the casing 5. Since in the practical embodiment of the invention the casing 5 will be made of metal, the reinforcement 9 forms a broad 105 seat upon the mouthpiece 4, preventing the weight of the casing 5 from marring the mouthpiece when resting thereon. The telephone receiver 1 will now be placed with its enlarged listening end in the casing by passing the smaller or hand portion through the open end of the slot or opening 10 until the 110

2
 receiver rests upon the reinforcement 14. On replacing the cover or cap 11 the plate 12 will engage or embrace the upper side of the hand portion of the receiver 1 and thus secure, lock the same to the casing 5. Now, by inserting through the opening 7 a suitable disinfecting agent, preferably such as will give off disinfecting vapors or fumes on burning, and lighting the same, say with a match, or by first lighting the disinfecting agent and then introducing it through the opening, the germicide fumes or vapors rising in the case 5 will be brought into intimate contact with the mouth and ear pieces respectively, and will thoroughly destroy any germs that may be adherent thereto. The necessary air to support combustion will find its way through the opening 7. The fumigating material may be made to burn for five or ten minutes, which time, considering the small and confined space to be acted upon, will be sufficient to thoroughly cleanse the telephone instruments. When the instruments have been acted on for a sufficient length of time the cover 11 may be removed, after which the receiver may be taken out and the mouth-piece of the transmitter may be unscrewed and the fumigating device may be released and removed from the transmitter.

30 It will thus be seen that there is provided a simple and easily applied device adapted to be attached to telephone instruments without disturbing their operative relation or removing them from the circuit, and by means of which the fumigation of those parts of the instruments liable to microbic contamination is effected without trouble.

I claim:—

1. A fumigator for telephone instruments comprising a casing provided with a receptacle for a fumigating agent and also having an opening for the mouth-piece of a telephone

transmitter, the said casing being adapted to be locked to and carried by the transmitter head through the intermediary of said mouth-piece, and said casing also having an opening for embracing the telephone receiver body with the hearing end thereof inferior to the casing.

2. A fumigator for telephone instruments comprising a casing, a receptacle for the fumigating agent at one end thereof, said receptacle being provided with an inlet opening, a removable cover at the other end thereof, a through passage into the receptacle adapted to receive the mouthpiece of a telephone transmitter, another opening in the receptacle extending to the covered end thereof and adapted to receive the hand portion of a telephone receiver, and a locking plate carried by the cover and movable into coaction with the telephone receiver opening.

3. A fumigator for telephone instruments comprising a receptacle having an open upper end and a contracted lower end, said casing being provided with an opening for the introduction of a fumigating agent, another opening extending from the upper end downward and having a rounded lower termination, a third opening below the last named opening and arranged to receive the mouthpiece of a telephone transmitter, whereby the casing is supported, and a cover for the open end of the casing having a locking plate for retaining the telephone receiver in the respective opening in the casing.

In testimony that I claim the foregoing as my own, I have hereto affixed my signature in the presence of two witnesses.

LOUIS I. SHRADER.
